UNITED STATES PATENT OFFICE.

HENRY C. BARLOW, OF GOLDDENDALE, WASHINGTON.

PIPE-WRENCH.

No. 810,365.

Specification of Letters Patent.

Patented Jan. 16, 1906.

Application filed June 22, 1905. Serial No. 266,482.

To all whom it may concern:

Be it known that I, HENRY C. BARLOW, a citizen of the United States, residing at Goldendale, in the county of Klickitat and State 5 of Washington, have invented a new and useful Pipe-Wrench, of which the following is a specification.

This invention relates to pipe and rod wrenches, and has for its object to simplify 10 and improve the construction and increase the efficiency and utility of devices of this character.

With these and other objects in view, which will appear as the nature of the invention is 15 better understood, the same consists in certain novel features of construction, as herein-after fully described and claimed.

In the accompanying drawings, forming a part of this specification, and in which corresponding parts are denoted by like designating characters, is illustrated the preferred form of embodiment of the invention capable of carrying the same into practical operation, it being understood that the invention is not 20 necessarily limited thereto, as various changes in the shape, proportions, and general assemblage of the parts may be resorted to without departing from the principle of the invention or sacrificing any of its advantages.

30 In the drawings thus employed, Figure 1 is a side elevation of the improved implement arranged for grasping a relatively small pipe; and Fig. 2 is a side view, partly in section, with the implement arranged for grasping a 35 relatively large pipe. Fig 3 is a rear elevation of the implement arranged as in Fig. 2.

The improved implement comprises a stock 10, having at one end a stationary jaw 11, formed with concaved surfaces 12 13, provided with spaced transverse teeth 14 15 and with semicircular spaced ears 16 17. A pin 40 18 is disposed through the ears 16 17 and the space between them and at one side of the center of the same, the object to be hereinafter explained. A movable jaw member 19 is formed with hook 20 at one end and a central semicircular disk 21 at the other end for position between the ears 16 17 and with an aperture 22 for receiving the pin 18 and larger in 45 diameter than the pin as shown in Fig. 2. The jaw member 19 is also formed with curved lateral shoulders 23 24 for bearing

constantly upon the ears 16 17 at the side opposite to the hooked terminal 20 of the movable jaw member, so that the strain is borne 55 almost entirely by the shoulder portion of the jaw member and the pin 18 relieved from transverse strain. Thus a comparatively light structure is capable of withstanding a very heavy strain, as will be obvious. The 6c inner face of the movable jaw member is provided with spaced transverse teeth 25, inclined reversely to the teeth 14 15 of the stationary jaw and for coaction therewith.

By this simple arrangement a very strong 65 and durable implement is produced which may be employed for grasping pipes or rods of a wide range of sizes by reason of the two concaved surfaces 14 15, as illustrated in Figs. 1 and 2, the inner cavity 14 in conjunction with the movable jaw member for grasping the larger pipes (indicated at 26 in Fig. 2) and the outer cavity 15 for grasping the smaller sizes in conjunction with the same movable jaw member, as indicated by dotted 70 lines 27 in Fig. 1.

The parts can be constructed from steel or iron, as preferred, and can be inexpensively manufactured, as there are few parts and require very little "fitting" or hand or machine 80 work to produce the same.

Having thus described the invention, what is claimed is—

In a wrench, a stock having a stationary jaw at one end with two or more concaved 85 surfaces having transverse spaced teeth, and with semicircular spaced ears having a transverse pin disposed at one side of the center thereof, a movable jaw member having a hook at one end and with spaced transverse 90 teeth in its inner face and a semicircular member bearing between said ears and with a transverse aperture for receiving said pin and larger than the same, said movable jaw having lateral shoulders bearing constantly 95 upon said spaced ears at the side opposite from said terminal hook.

In testimony that I claim the foregoing as my own I have hereto affixed my signature in the presence of two witnesses.

HENRY C. BARLOW.
